(57) **CLAIM**

The ornamental design for a combined hair curling tool as shown and described.

DESCRIPTION

FIG. 1 is a perspective view of a combined hair curling tool showing our new design in a combined configuration of use; FIG. 2 is another perspective view thereof; FIG. 3 is a front view thereof; FIG. 4 is a rear view thereof; FIG. 5 is a left side view thereof; FIG. 6 is a right side view thereof; FIG. 7 is a top plan view thereof; FIG. 8 is a bottom plan view thereof; FIG. 9 is an exploded perspective view of the combined hair curling tool; and,

FIG. 10 is a bottom perspective view of the top structure of the combined hair curling tool in a second configuration of use with the bottom structure omitted.

The broken lines immediately adjacent to the claim depict the bounds of the claimed design, while all other broken lines are directed to environment. The broken lines form no part of the claimed design.

1 Claim, 10 Drawing Sheets
